UNITED STATES PATENT OFFICE.

JOHN DOORENBOS, OF KALAMAZOO, MICHIGAN, ASSIGNOR TO NATIONAL GAS LIGHT CO., OF KALAMAZOO, MICHIGAN, A CORPORATION OF MICHIGAN.

GAS-BURNER.

No. 840,881.

Specification of Letters Patent.

Patented Jan. 8, 1907.

Application filed April 20, 1906. Serial No. 312,847.

To all whom it may concern:

Be it known that I, JOHN DOORENBOS, a citizen of the United States, residing at Kalamazoo, in the county of Kalamazoo and State of Michigan, have invented a new and useful Improvement in Gas-Burners, of which the following is a specification.

My invention relates particularly to regulating means for gas-burners; and my primary object is to provide improved means for regulating the passage of gas through a Bunsen burner, the device being adapted to control the feed of gas through the burner regardless of the variation of pressure of gas in the mains.

My invention is illustrated in its preferred embodiment in the accompanying drawings, in which—

Figure 1 represents a Bunsen burner constructed in accordance with my invention, and Fig. 2 an enlarged broken vertical section through the base of the burner and showing the pressure-regulating means.

In the construction shown, A represents my improved burner, and B a chimney support of well-known construction. The burner comprises a nipple a, adapted to be secured upon a chandelier-arm or a bracket-arm, said nipple being surmounted by a removable hollow cap a', a cylinder a², carried by the upper end of the nipple a and confined within the cap a', a self-adjusting needle-valve a³, carried by a disk a⁴, movable within the cylinder a², and a Bunsen-burner tube or mixer-tube a⁵, having air-inlets a⁶ above the cap a'. As shown, the nipple a is internally threaded at its lower end at a⁷ and has formed in it a chamber a⁸, from which a passage a⁹ extends upwardly to admit

gas beneath the disk a⁴, and a passage a¹⁰ extends laterally, communicating with a vertical passage a¹¹, which in turn communicates with a chamber a¹², formed between the cylinder a² and the interior sur-

face of the cap a'. The nipple a preferably has at its top a boss a¹³, through which the passage a⁹ extends, and the cylinder a² is open at its upper end and has an inturned flange a¹⁴ at its lower end, which fits upon

the boss a¹³ and is secured thereon by a bur a¹⁵. The needle-valve extends, when the disk a⁴ is at the lower end of its traverse, into a gas-orifice a¹⁶, with which the cap a' is provided at its apex, a passage being afforded

for gas, however, in this position. The lateral passage a¹⁰ is guarded by a valve a¹⁷, which has a threaded shank a¹⁸ extending through the opposite wall of the nipple. The valve and its shank may be formed by a screw having a knurled head to enable adjustment to be made and having a reduced extremity forming the valve. The cap a' is formed with a reduced upper portion a¹⁹, which is externally threaded to receive the internally-threaded lower end of the burner-tube a⁵. The formation is such as to provide a shoulder a²⁰, upon which the chimney-support B rests outside of the base of the burner-tube. The bur a¹⁵ may be formed by striking the portion of the boss a¹³ which extends above the flange a¹⁴ of the cylinder a² with a cold-chisel, so that passages will be provided enabling the gas to pass freely to all parts of the lower surface of the disk a⁴.

From the foregoing detailed description the operation of the valve will be readily understood. In the normal operation the gas is admitted through the lateral passage a¹⁰, the vertical passage a¹¹, and the annular chamber a¹² to the orifice a¹⁶, and the pressure is also admitted to the cylinder a² beneath the disk a⁴. The pressure causes the needle-valve to rise and obstruct the orifice a¹⁶ until the back pressure due to the constricted opening, taken in connection with the weight of the valve, is sufficient to balance the lifting force upon the valve. It will be obvious, therefore, that the device may be adjusted to varying pressures by regulating the position of the valve a¹⁷, whose stem projects laterally from the nipple a to enable this purpose to be accomplished.

It is obvious that the device may be advantageously employed in connection with Bunsen burners of all forms and types, and the device is especially valuable in connection with incandescent gas-lamps of all kinds.

The foregoing detailed description has been given for clearness of understanding only, and no undue limitation is to be understood therefrom.

What I regard as new, and desire to secure by Letters Patent, is—

1. The combination with a Welsbach burner having a gas-orifice and a mixer-tube into which said orifice opens, a valve controlling said orifice and equipped with a piston, a cylinder in which said piston moves, a pas-

- sage leading to the cylinder beneath the piston, a passage extending around the cylinder to said first-named orifice, and a valve controlling said last-named passage.
- 5 2. The combination of a nipple having a chamber therein and a vertical passage from said chamber and a lateral passage from said chamber, a laterally-extending threaded valve connected with said nipple and controlling said lateral passage, a cap surmounting the nipple and having an orifice, a cylinder within the cap surmounting the nipple, and a piston within the cylinder equipped with a valve controlling said orifice.
- 15 3. The combination of a nipple having a chamber with a central vertical passage therefrom and a lateral passage, a cylinder connected with the upper portion of said nipple into which said vertical passage opens, a piston within said cylinder, a cap surmount-
- ing said nipple and inclosing said cylinder, said cap having a central orifice at its apex, and a needle-valve extending into said orifice and equipped with a piston working in said cylinder, for the purpose set forth. 25
4. The combination of a nipple having a chamber with two passages leading therefrom, a cylinder in communication with one passage, a piston working in said cylinder and equipped with an upward-extending 30 valve, a cap surmounting said nipple and forming with the cylinder an annular passage for gas, the said cap having a reduced externally-threaded upper portion, and a mixer-tube screwed on said cap.

JOHN DOORENBOS.
